FUEL INJECTION APPARATUS

Albert T. Bremser, Sidney, N. Y., assignor to
 Bendix Aviation Corporation, South Bend, Ind.,
 a corporation of Delaware

Application April 1, 1942, Serial No. 437,154

20 Claims. (Cl. 103—41)

This invention relates to fuel injection apparatus and more particularly to means for delivering fuel under pressure to the cylinders of a solid fuel injection engine.

One of the objects of the present invention is to provide novel apparatus of the above character whereby the fluid pressure of the fuel in the delivery line is relieved after each injection of fuel into the engine cylinder.

Another object of the invention is to provide a novel fuel injection pump including a novel delivery valve whereby pressure surges in the delivery line between the pump and the engine cylinder are effectively damped or substantially eliminated.

A further object is to provide a novel fuel pump adapted to provide supply line relief for the pressure in the delivery line after the injection stroke without danger of introducing air pockets or creating a suction in said delivery line.

Still another object is to provide a novel fuel injection pump adapted for feeding fuel to an injection nozzle of the open type so as to obviate any dribbling of fuel from said nozzle after the injection stroke of the pump.

A still further object of the invention is to provide a novel apparatus of the above nature in which the pressure in the delivery line is relieved by timely communication of the latter with the fuel supply or by-pass line.

The above and further objects and novel features of the invention will more fully appear from the following detailed description when the same is read in connection with the accompanying drawing. It is to be expressly understood, however, that the drawing is for the purpose of illustration only and is not intended as a definition of the limits of the invention, reference for this latter purpose being had primarily to the appended claims.

In the drawing, wherein like reference characters refer to like parts throughout the several views,

Fig. 1 is a side elevation, partly in section and with parts broken away, of one form of fuel injection pump and delivery valve embodying the present invention; and,

Fig. 2 is a similar view of another embodiment of the invention with the lower end thereof broken away.

One embodiment of the present invention is illustrated in Fig. 1, by way of example, in the form of a fuel injection pump comprising a metallic casing 10, in the central bore of which a cylinder 11 and a delivery valve adapter 12 are

held in end to end engagement by a combination gland nut and casing member 13, the latter having threaded engagement with the upper, inner end of casing 10. Slidably mounted for reciprocating movement in cylinder 11 is a piston or plunger 14, which is preferably actuated and controlled in any suitable and well-known manner, such as shown in Bremser Patent No. 2,265,997. To adjust the angular position of said piston relative to said cylinder, a rack and pinion mechanism of well-known construction is preferably provided, only rack 15 of said mechanism being shown in the drawing.

Extending radially through the wall of cylinder 11 is a fuel inlet or suction port 16 which connects the bore of said cylinder with an annular channel 17 provided in casing 10, said channel communicating with the fuel supply source (not shown) through an inlet passage 18. Disposed beneath port 16 and extending radially through the wall of said cylinder is a relief or by-pass port 19 which also connects with channel 17. The latter is preferably formed in a hard metal sleeve or insert 20 around which casing 10 may be cast, said sleeve, as shown, being provided with a baffle 21 extending for at least a portion of its periphery to separate the channel portions connecting with ports 16 and 19.

To control the fuel flow from the pressure chamber which is formed in the upper end of cylinder 11 between piston 14 and adapter 12, a novel delivery valve comprising a stem 22 and a head 23 is slidably mounted for reciprocating movement in the central bore of said adapter. In the closed position thereof, valve 22, 23 has the reduced lower end of stem 22 in fluid-tight engagement with an internally extending shoulder or seat 24 in the lower end of said adapter. As shown, the engaging surfaces of said shoulder and stem are conical in shape but a flat or other type valve seat may be employed. A second fluid seal is obtained at the upper end of valve 22, 23 by engagement of cylindrical portion or retraction collar 25 of stem 22 with the wall of the adapter bore. A plurality of axial flutes 26 are preferably formed in the periphery of said valve stem to provide fuel passages from the lower end of said stem to the cylindrical portion 25. A spring 27 is contained in member 13 and engages head 23 of said valve to urge the latter in the direction of seat 24, said spring being guided by a member 28 which also serves to limit the upward movement of said valve. The upper end of member 13 is adapted to have a delivery conduit (not shown) connected thereto at 29, said conduit

communicating with the fuel spray nozzle at the engine cylinder.

During the upward stroke of piston 14, as soon as port 16 is covered, valve 22 is lifted by the fuel pressure built up above the piston and fuel flows past seat 24, along flutes 26 into the delivery line and thence to the delivery nozzle at the engine cylinder. To cut off the fuel injection during the upward or pressure stroke of plunger 14 at a desired point in the stroke, a helical groove 30 is provided in the wall of said plunger for cooperation in a well-known manner with by-pass port 19, said groove being connected to the pressure chamber of the pump by an axial passage 31 and a transverse passage 32. The latter extends diametrically through said plunger and has one end thereof connecting with groove 30 and the other end with a second helical groove 33 which is similar to groove 30, said grooves being symmetrically disposed in respect to the axis of said plunger.

Novel means are provided for relieving the pressure and eliminating pressure surges in the delivery line after fuel injection cut-off and, as shown, said means comprise a central relief passage 34 extending through valve head 23 to communicate with a central recess 35 of enlarged diameter in valve stem 24, said head being threadedly secured in the upper end of said recess. A check valve 36, preferably of the ball and spring type, is disposed in recess 35 to prevent fuel flow from said recess through passage 34, i. e., in the direction of the delivery line, the lower portion of said recess having a decreased diameter to provide a shoulder 37 for supporting the spring of said valve. A plurality of radial passages 38 connect recess 35 to an annular groove 39 provided in the internal wall of adapter 12 above seat 24. Groove 39 communicates with an annular groove 41 in the base of said adapter by means of a plurality of connecting passages 42, the latter groove being in turn connected by an axially extending passage 43 in the wall of cylinder 11 to a relief port 44 which is coaxial with and disposed diametrically opposite by-pass port 19 to connect with the bore of said cylinder. The outlet of port 44 is similar in shape to that of port 19 so that said ports are simultaneously connected to and disconnected from each other and the pressure chamber of the pump by helices 30 and 33, respectively, during the piston stroke.

In operation, the fuel pressure in the pressure chamber begins to build up during the upstroke of the piston when the edge of the latter moves past inlet port 16 to close said port. The fuel pressure acts to raise valve 22, 23 from seat 24 but no fuel flow into the delivery line occurs until portion 25 of said valve stem clears the upper edge of adapter 12. The initial upward movement of the valve eliminates any voids in the delivery line and mechanically compresses any trapped gases, thereby placing the fuel in said delivery line under a suitable pressure. When retraction collar 25 moves out of the bore of adapter 12, fuel is introduced into the delivery line from the pressure chamber and delivery continues until helices 30 and 33 overlap ports 19 and 44, respectively. Fuel is then by-passed through passages 31 and 32 and port 19 to the supply line and the fuel pressure in cylinder 11 drops to the supply line pressure, permitting spring 27 to cause valve 22, 23 to move downward into closed position. The pressure in the delivery line is relieved by the downward movement

of said valve and by the flow of fuel through the system of relief passages connecting passage 34 to port 44 and thence across plunger 14, through port 19 to the fuel supply line. The relief passage system from passage 34 to port 44 acts not only to relieve the pressure in the delivery line but substantially eliminates or effectively damps the pressure surges which normally occur upon the closing of the delivery valve. This is of utmost importance, particularly with a nozzle of the open type or one adapted to operate at relatively low fuel injection pressures, since it prevents any dribbling of fuel into the engine cylinder after the cut-off point. It is to be noted that the relief passages are connected to the fuel supply line during portions of the upstroke and the downstroke of the pump plunger, i. e., during the period that helices 30 and 33 are in communication with ports 19 and 44, so that there is a sufficient opportunity for elimination of pressure surfaces. When the by-pass port is closed to the pressure chamber, i. e., during the suction part of the downstroke, the relief passages are also cut off from both the supply line and the pressure chamber. As a result, the suction set up in the pressure chamber during this portion of the downstroke does not affect the delivery line pressure. The relief of the delivery line pressure in this manner without the creation therein of suction pressures materially increases the efficiency of the fuel delivery, particularly when the engine is operating at high speeds.

Central passage 31 may be eliminated if the pump is to be utilized with a differential pressure type nozzle, in which event, after the fuel injection cut-off, i. e., after helices 30 and 33 overlap ports 19 and 44, the fuel is by-passed from the pump pressure chamber through channel 39, passages 42 and 43, port 44, and across the pump plunger to port 19 and the supply line. The valve 22 remains lifted from its seat 24 during this by-pass portion of the stroke.

Another embodiment of the invention is illustrated in Fig. 2 and the structure thereof, except for the delivery valve and the diameter of the adapter bore, is substantially similar to the above-described embodiment. Accordingly, like parts of the two embodiments or parts thereof which differ only dimensionally are designated by like numerals. The novel delivery valve 45, shown in Fig. 2, is slidably mounted in the bore of adapter 12 and when in closed position the lower end of said valve seats on shoulder 24 to form a fluid-tight seal. When valve 45 is raised, groove 39 communicates with the pressure chamber and the latter is, in turn, connected through a suitable fluid passageway in said valve to the delivery line. As shown, said passageway comprises a central axial recess 46 extending from the upper end of said valve to a point adjacent the lower end thereof and a plurality of radial passages 47 which connect with said recess at one end and open into groove 39 at the other end.

In operation, when plunger 14 covers inlet port 16 on the upstroke to begin fuel pumping, valve 45 is raised and connects the pressure chamber to groove 39 and, therefore, to the delivery line which is in continuous communication with said groove through passages 46, 47. Fuel delivery then takes place until, at a later point in the plunger upstroke, helices 30 and 33 overlap ports 19 and 44, and thereby connect the pressure chamber and groove 39 to the supply line through passage 31 and passages 42 and 43, respectively, or through only the latter passages when passage

31 is eliminated as pointed out above. When the pump plunger reaches its point of by-pass or its top dead center position, depending upon whether or not there is a passage 31 in the plunger, spring 27 closes valve 45, which seats on shoulder 24, but the delivery line remains connected to the supply line through recess 46, radial passages 47 and the fuel passageway 42, 43 from groove 39 to port 44. Accordingly, the pressure in the delivery line is relieved across the pump plunger. However, as in the preceding embodiment, the delivery line is not subjected to the suction created in the pressure chamber during the piston downstroke because the relief port 44 is disconnected from said chamber concurrently with 15 by-pass port 19.

There is thus provided novel fuel injection apparatus wherein the fuel in the delivery space between a pump and an injection nozzle is maintained at substantially the same pressure as the supply line, except during the effective portion of the pump stroke when fuel is being delivered to the nozzle. Novel means permit relief of the pressure in the delivery line after each injection of fuel into the engine cylinder so as to substantially eliminate dribbling from the fuel nozzle without introducing air pockets or producing undue suction in the line. There is additionally provided a novel delivery line pressure relief system wherein valve means act to obviate pressure surges in the line. As a result, the novel pump means is extremely effective for injecting fuel to nozzles adapted to function at low injection pressures, particularly nozzles of the open type. Moreover, at high speed operation, the novel structure of the instant invention acts to increase the volumetric efficiency of the fuel delivery pump.

Although only two embodiments of the present invention have been illustrated and described, it is to be expressly understood that the same is not limited thereto. For example, various changes may be made in the design and arrangement of parts illustrated without departing from the spirit and scope of the invention, as 45 will now be apparent to those skilled in the art. For a definition of the limits of the invention, reference is had primarily to the appended claims.

What is claimed is:

1. In a fuel injection pump, means comprising a pressure chamber and including a plunger, said plunger operating as a bypass valve to connect said chamber to the fuel supply line during a predetermined portion of the stroke thereof, a delivery valve controlling the fuel flow from said chamber to a delivery line, and means constituting a relief passageway for connecting the delivery line to a fuel supply line during the entire by-pass portion of the piston stroke, said last-named means comprising passages through said delivery valve and said plunger.

2. In a fuel injection pump, means comprising a pressure chamber and including a plunger, a delivery valve controlling the fuel flow from said chamber to the delivery line, and means constituting a relief passageway connecting with the delivery line, said plunger having passages therein adapted to concurrently connect said pressure chamber and said passageway to a region of relatively low pressure, such as a fuel supply line, during a predetermined portion of said plunger stroke, the connection between said chamber and said low pressure region being independent of said passageway.

3. In a fuel injection pump, means comprising a pressure chamber and including a plunger, a delivery valve controlling the fuel flow from said chamber to a delivery line, and means constituting a relief passageway connecting with the delivery line when said valve is closed, said plunger acting as a valve to concurrently connect said pressure chamber and said passageway to a region of low pressure, such as a fuel supply line, the connection between said chamber and said low pressure region being independent of said passageway.

4. In apparatus of the class described, a cylinder having a by-pass port, a relief port and an inlet port, said by-pass and inlet ports connecting with a fluid supply line, a piston reciprocably mounted in said cylinder, an adapter mounted adjacent one end of said cylinder to form a pressure chamber with said piston and cylinder, a delivery valve carried by said adapter to control the fluid flow from said chamber to a delivery line, said valve having fluid-tight engagement with said adapter when in closed position, means comprising a relief passage from said relief port to a port in said adapter, the latter port communicating at all times with a passage in said valve connecting with the delivery line, and check valve means in said last-named passage permitting fluid to flow from said delivery line to said relief port, said piston connecting said relief port and said pressure chamber to the supply line during a predetermined portion of the stroke thereof.

5. In apparatus of the class described, a cylinder having an inlet port, a by-pass port and a relief port, said by-pass port and inlet port connecting with a fuel supply line, a piston slidably mounted in said cylinder, an adapter mounted adjacent one end of said cylinder to form a pressure chamber with said piston and cylinder, a delivery valve slidably mounted in the bore of said adapter to control the fuel flow from said chamber to a delivery line, said valve having a passage therein in constant communication with the delivery line and with a groove in said adapter bore, said groove connecting with said pressure chamber when said valve is in open position to deliver fuel through said valve passage, and means comprising a relief passage from 50 said groove to said relief port, said port being connected by said piston to the fuel supply line during fuel by-pass.

6. In apparatus of the class described, a cylinder having an inlet port, a by-pass port and a relief port, said by-pass port and inlet port connecting with a fuel supply line, a piston slidably mounted in said cylinder, an adapter mounted adjacent one end of said cylinder to form a pressure chamber with said piston and cylinder, said piston operating as a valve to control the flow of fuel between said chamber and said inlet and by-pass ports, a pressure-actuated delivery valve slidably mounted in the bore of said adapter to control the fuel flow from said chamber to a delivery line, said valve having an open passage therein connecting said delivery line with a groove in said adapter bore, said groove connecting with said pressure chamber when said valve is in open position, and means comprising a relief passage from said groove to said relief port, the latter being connected by said piston to said by-pass port during fuel by-pass.

7. In a fuel pump having a pressure chamber 75 and an adapter, a delivery valve slidably mounted

in the bore of said adapter to control the fuel flow from said chamber to the delivery line, said valve comprising a stem portion adapted to have fluid-tight plunger engagement at the upper end thereof and fluid-tight seating engagement at the lower end thereof with said adapter, the engaging surfaces being disengaged from said adapter when said valve is in open position, at least one radially extending passage in said valve stem between said upper and lower engaging surfaces, a relief passage in said valve communicating at one end with the delivery line and at the other end with a relief passage in said adapter through said radially extending passage, and a check-valve in said first-named relief passage operative to prevent fuel flow in the direction of the delivery line.

8. In fuel injection apparatus, a plunger pump adapted to receive liquid fuel from a supply line and deliver the same under pressure to a delivery line, and means having passages controlled by the pump plunger for connecting said delivery and supply lines to each other during a predetermined portion of the stroke of said plunger and including other passages for connecting the pressure chamber of said pump to said supply line during said portion of the plunger stroke independently of the position of said delivery valve.

9. In fuel injection apparatus, a plunger pump adapted to receive liquid fuel from a supply line and deliver the same under pressure to a delivery line, a delivery valve for controlling the connection between said pump and said delivery line, and means including a fuel passage in said delivery valve for connecting said delivery and supply lines to each other, the flow of fuel from the delivery line to the supply line being controlled by the plunger of said pump.

10. In fuel injection apparatus, a plunger pump adapted to receive fuel from a supply line and deliver the same under pressure to a delivery line, normally closed delivery valve means for controlling the connection between said pump and said delivery line, and means including passages controlled by the plunger of said pump for connecting the pressure chamber of said pump and said delivery line to said supply line when said valve means are closed during a predetermined portion of the stroke of said plunger.

11. In fuel injection apparatus, a pump having a reciprocating plunger, said pump being adapted to receive liquid fuel from a supply line and deliver the same to a delivery line under pressure, delivery valve means for controlling the connection between the pressure chamber of said pump and said delivery line, means including a passage in said valve means for connecting said delivery line with a relief port in the wall of the pump cylinder, and a one-way check-valve in said passage adapted to permit flow from said delivery line, said plunger being adapted to connect said relief port with said supply line during a predetermined portion of the stroke thereof.

12. In fuel injection apparatus, a fuel pump comprising a cylinder and a piston operable therein, said cylinder having inlet and by-pass ports controlled by said piston and connected to a source of fuel supply, the discharge side of said pump being connected to a fuel delivery line, means controlling said connecting means including a resiliently closed delivery valve, and means including a passage in said valve and passages controlled by said plunger for connecting said delivery line to said source of fuel supply.

13. In fuel injection apparatus, a fuel pump comprising a cylinder and a piston operable therein, said cylinder having port means through which the flow of fuel is controlled by said piston, a normally closed pressure operated delivery valve for controlling communication between the pressure chamber of said pump and a delivery line, and means including a passage controlled by said piston for establishing communication between said delivery line and said port means and another passage for concurrently connecting said pressure chamber with said port means immediately after the effective pumping stroke of the plunger while said delivery valve is in closed position.

14. In fuel injection apparatus, pump means comprising a cylinder and a piston operable therein, said cylinder having port means in the wall thereof controlled by said piston and connected with a region of low pressure, such as a source of fuel supply, means connecting the discharge side of said pump with a delivery line, a delivery valve for controlling flow through said connecting means, and means including a check valve controlled passage in said delivery valve and a passage controlled by said piston for establishing communication between said delivery line and said low pressure region independently of the pressure chamber of said pump means during at least a portion of the time that said delivery valve is in closed position.

15. In fuel injection apparatus, a plunger pump adapted to receive liquid fuel from a supply line and deliver the same under pressure to a delivery line, a delivery valve for controlling flow of said fuel between said pump and delivery line, means including a passage controlled by the pump plunger for establishing communication between said delivery and supply lines independently of the pressure chamber of said pump, during a predetermined portion of the stroke of said plunger while said delivery valve is in closed position, and a one-way check-valve in said passage adapted to permit flow from said delivery line.

16. In fuel injection apparatus, a plunger pump adapted to receive liquid fuel from a source of supply and deliver the same under pressure to a delivery line, valve means for controlling the flow of said fuel between said pump and delivery line, and means controlled by the pump plunger for establishing communication between said delivery line and a region of low pressure independently of the pressure chamber of said pump during a predetermined portion of the stroke of said plunger while said valve means is in closed position, said communication establishing means including a one-way check-valve adapted to permit flow from said delivery line.

17. In a fuel injection pump, means including a reciprocable plunger forming a pressure chamber adapted to be connected with a fuel supply line, a delivery valve controlling the flow of fuel from said chamber to a delivery line, said plunger being operable as a by-pass valve to connect said chamber to said supply line independently of said delivery valve during a predetermined portion of the pressure stroke of the plunger, and means constituting a relief passageway adapted to connect said delivery line to said supply line independently of said pressure chamber during said portion of the plunger stroke when said delivery valve is in closed position.

18. In a fuel injection pump, means including a reciprocable plunger forming a pressure cham-

ber adapted to be connected with a fuel supply line, a delivery valve controlling the flow of fuel from said chamber to a delivery line, said plunger being operable as a by-pass valve to connect said chamber to said supply line independently of said delivery valve during a predetermined portion of the pressure stroke thereof, and means constituting a relief passageway for connecting said delivery line to said supply line independently of said pressure chamber while said chamber and supply line are in communication with each other through said by-pass connection.

19. In fuel injection apparatus, a plunger pump adapted to receive liquid fuel from a supply line and deliver the same under pressure to a delivery line, valve means for controlling the connection between the pressure chamber of said pump and said delivery line, and means including a passage controlled by the plunger of said pump for connecting said pressure chamber and

5
said delivery line to a region of low pressure, such as said supply line, during a portion of the stroke of the plunger immediately following the closure of said valve means.

20. In fuel injection apparatus, a pump having a reciprocating plunger, said pump being adapted to receive liquid fuel from a supply line and deliver the same to a delivery line under pressure, delivery valve means for controlling the connection between the pressure chamber of said pump and said delivery line, means including a passage for connecting said delivery line with a relief port in the wall of the pump cylinder, said plunger being adapted to connect said relief port with a region of relatively low pressure, such as said supply line, during a predetermined portion of the stroke thereof, and a one-way check valve in said passage adapted to permit flow from said delivery line.

ALBERT T. BREMSER.
